UNITED STATES PATENT OFFICE.

EDWARD R. THIELER, OF HOBOKEN, NEW JERSEY.

DESIGN FOR A PLATE.

44,154.

Specification for Design.

Patented June 3, 1913.

Application filed April 1, 1913. Serial No. 758,271. Term of patent 7 years.

To all whom it may concern:

Be it known that I, EDWARD R. THIELER, a citizen of the United States, residing at Hoboken, in the county of Hudson and State of New Jersey, have invented a new, original, and ornamental Design for Plates, of which the following is a specification, reference being had to the accompanying drawing, forming a part thereof.

The drawing shows a plan view of a plate illustrating my design.

I claim—

The ornamental design for a plate as shown.

EDWARD R. THIELER.

Witnesses:

HUGO MOCK,
MARY PERRY.
